United States Patent Office

Des. 197,826
Patented Mar. 24, 1964

197,826

TOASTER

Dominic J. De Fano, River Grove, Ill., assignor to
McGraw-Edison Company, Milwaukee, Wis., a
corporation of Delaware

Continuation of design applications Ser. No. 69,351, Mar.
21, 1962 and Ser. No. 69,352, Mar. 21, 1962. This
application Oct. 30, 1962, Ser. No. 72,368

Term of patent 14 years

(Cl. D81—10)

Fig. 4

Fig. 5

Fig. 6

Fig. 7

Fig. 8

*Fig. 9**Fig. 10*FIG. 1 is a perspective view of a toaster embodying my new design;

FIG. 2 is a right side elevation thereof;

FIG. 3 is a front elevation view thereof;

FIG. 4 is a rear elevation view thereof;

FIG. 5 is a top plan view thereof;

FIG. 6 is a perspective view of a second embodiment of the invention identical to the embodiment of the invention of FIGS. 1 through 5 except for the omission of the upper lever handle and associated slot shown in dotted lines in FIGS. 1 through 3 and 5;

FIG. 7 is a perspective view showing the front and control side of a third embodiment of the invention;

FIG. 8 is a rear elevation of the toaster of FIGURE 7;

FIG. 9 is a left side elevation of the toaster of FIGURE 7; and

FIG. 10 is a top plan view of the embodiment of FIGURE 7.

This application is a continuation of my prior co-pending applications, Serial Nos. D. 69,351 and D. 69,352, both filed on March 21, 1962, and both now abandoned.

The dominant features of my design reside in the portions shown in full lines.

I claim:

The ornamental design for a toaster, as shown and described.
